UNITED STATES PATENT OFFICE

DAVID M. BENFORD, OF NEW YORK, N. Y.

DESIGN FOR AN ELECTRIC NECKTIE RESTORER

Application filed January 30, 1931. Serial No. 38,504. Term of patent 14 years.

To all whom it may concern:

Be it known that I, DAVID M. BENFORD, a citizen of the United States, residing at the borough of Bronx, New York city, in the county of Bronx and State of New York, have invented a new, original, and ornamental Design for an Electric Necktie Restorer, of which the following is a specification, reference being had to the accompanying drawings, forming part thereof,

Fig. 1 is a top face view of an electric necktie restorer, showing my new design.

Fig. 2 is an edge view of the same.

Fig. 3 is a bottom face view of the same.

I claim:

The ornamental design for an electric necktie restorer, as shown.

In testimony whereof I have affixed my signature.

DAVID M. BENFORD.
